CLAIM

The ornamental design for laterally elongated eyewear, as shown and described.

DESCRIPTION

FIG. 1 is a perspective view of laterally elongated eyewear as disposed upon a head;

FIG. 2 is a side elevational view of the laterally elongated eyewear;

FIG. 3 is a front elevational view of the laterally elongated eyewear; and,

FIG. 4 is a bottom planar view of the laterally elongated eyewear.

The broken line disclosure of a head in FIG. 1 is for illustrative purposes only and forms no part of the claimed design.
